UNITED STATES PATENT OFFICE.

CHARLES L. NEWCOMB, OF HOLYOKE, MASSACHUSETTS, ASSIGNOR TO THE DEANE STEAM PUMP COMPANY, OF SAME PLACE.

PUMPING-ENGINE.

SPECIFICATION forming part of Letters Patent No. 580,194, dated April 6, 1897.

Application filed February 15, 1896. Serial No. 579,449. (No model.)

To all whom it may concern:

Be it known that I, CHARLES L. NEWCOMB, a citizen of the United States, residing at Holyoke, in the county of Hampden and State of Massachusetts, have invented a new and useful Improvement in Pumping-Engines, of which the following is a specification, accompanied by drawings forming a part of the same, in which—

10 Figure 1 is a top view of a pumping-engine embodying my improvement. Fig. 2 is a side view with a portion shown in section on line 22, Fig. 1. Fig. 3 is an end view of the pump piston-rod. Fig. 4 is a vertical sectional view 15 of the cross-head connecting with the steam-piston, the section being shown on line 4, Fig. 2; and Fig. 5 is an end view of the cross-head connected with the driving-shaft, the pump piston-rod being shown in sectional view on 20 line 5, Fig. 2.

Similar letters refer to similar parts in the different figures.

The pumping-engine which forms the subject of my present invention comprises a 25 pump-cylinder and a steam-cylinder with their inclosed pistons and a shaft driven independently of the steam-cylinder; and the object of my present invention is to provide means by which the piston of the pump-cylinder can be operatively connected with either 30 the driving-shaft or the piston of the steam-cylinder, so the pump-piston can be actuated directly from the steam-cylinder or from the rotating driving-shaft, as may be desired; and 35 my invention consists in the construction and arrangement of parts, as hereinafter described, and pointed out in the annexed claims.

In the accompanying drawings I have represented my invention as embodied in a duplex pumping-engine comprising two pump-cylinders and two steam-cylinders and a common driving-shaft. The actuating mechanism by which the pump-pistons are moved is, however, the same upon both sides of the 45 pumping-engine, and a description of one side will therefore serve as a description of the opposite side. The pump-cylinders and their inclosed pistons are of the ordinary and well-known form of construction, and therefore

the pump-cylinders are represented in the drawings by top and side views only, their inclosed pistons not being shown.

A denotes the framework of the pumping-engine, and A' A' the pump-cylinders.

B B denote the steam-cylinders, one of which 55 is shown in central sectional view in Fig. 2. The steam-cylinders are each provided with a steam-chest B' and slide-valve B², having a valve-stem B³, by which the steam-passages to the cylinder B are controlled in the usual 60 manner. Each of the steam-cylinders B contains a reciprocating piston B⁴, attached to a hollow piston-rod B⁵, which extends in opposite directions from the piston B⁴ and passes through the stuffing-boxes B⁶ B⁶ at opposite 65 ends of the steam-cylinder. One end of the hollow piston-rod B⁵ is attached to a reciprocating head C, carried upon the end of the hollow piston-rod. The head C is provided with a lug C', connected by a link C² with an 70 arm C³, which is attached to a rock-shaft C⁴, journaled in the framework of the machine and provided at its opposite end with a radial arm operatively connected with the reciprocating valve-stem upon the opposite side of 75 the pump. Similarly the corresponding heads carried upon the opposite hollow piston-rod of the pump is connected in like manner with a rock-shaft C⁵, journaled in the framework of the machine and provided with a radial arm C⁶, connected by a link C⁷ with the valve-stem B³, so the reciprocating motion of the heads C will actuate the steam-valves 80 upon the opposite side of the pump.

Journaled in the framework of the pump is 85 a shaft D, carrying a belt-pulley D', by which the shaft D is driven, and also a pinion D² in mesh with a gear D³ on a shaft D⁴, provided at its ends with crank-plates D⁵ D⁶, carrying crank-pins D⁷, Fig. 2, which are connected by 90 links D⁸ with reciprocating cross-heads D⁹, sliding in ways formed in the framework of the pump.

The pump-pistons, which are inclosed in the cylinders A' A' and not shown in the drawings, are carried upon piston-rods E E, which pass through the hollow steam piston-rods B⁵, Fig. 2, and are enlarged near their ends and

provided with a hexagonal section E', to which a wrench is applied in order to turn the piston-rod, as hereinafter mentioned.

The end of the piston-rod E is provided with lugs E² E² upon diametrically opposite sides of the piston-rods, as represented in Fig. 3, and a short distance from the end of the piston-rod and upon the opposite side of the hexagonal section E' are similar lugs E³ E³, projecting from the piston-rod and in a plane at right angles with that of E². The head C is provided with a circular chamber F, concentric with the piston-rod E, and having upon one side an elongated opening F', Fig. 4, having parallel sides F² F², forming lips F³ F³.

In Figs. 2 and 4 of the drawings the piston-rod E is shown as operatively connected with the reciprocating head C, and the connection of the head C and piston E is effected by moving the head C along the rod E until the lugs E² E³ are inclosed in the circular chamber F and turning the piston-rod E to bring the lugs E³ in a plane at right angles with that of the elongated opening F', so the ends of the lugs E³ will be held by the lips F³, causing the reciprocating motion of the head C, as it is moved by the steam piston-cylinder B⁴, to be imparted to the piston-rod E and its connected piston inclosed in the pump - cylinder A'. When the piston-rod E is turned in position to connect it with the head C, as shown in Figs. 2 and 4, lugs E² at the end of the piston-rod E correspond with an elongated opening G' in the cross-head D⁹, which communicates with a circular chamber G in the cross-head D⁹ and concentric with the piston-rod E, and in this position the cross-head D⁹ and piston-rod E are each capable of independent movement, as the cross-head D⁹ is capable of moving back and forth over the end of the piston-rod E and the lugs E² E².

The piston-rod E is disconnected from the head C and connected with the cross-head D⁹ as follows: The cross-head D⁹ is moved over the end of the piston-rod until the lugs E² are brought within the circular chamber G. A wrench is applied to the hexagonal section E' and the piston-rod E turned one-quarter of a revolution, bringing the lugs E² into a plane at right angles with the elongated opening G', so they will be locked in the chamber G, and at the same time bringing the lugs E³ into the plane of the elongated opening F', so the head C can be moved independently of the rod E, the piston - rod E being then driven by the cross-head D⁹.

The valve mechanism by which the passage of steam to the steam-cylinders B is controlled is connected to the heads C, and is therefore directly connected with the steam-pistons B⁴, so that whenever steam is shut off from the steam-cylinders the heads C and connected valve mechanisms are thrown out of action, allowing the piston-rods E and connected pump-pistons to be actuated by power re-

ceived through the belt-pulley D', thereby allowing the pump to be driven directly from a counter-shaft or other shafting of a mill, and whenever the shafting of the mill is stopped the pump may be driven by steam applied through the steam-cylinders B. The heads C and cross-heads D⁹ are provided with holes to receive a pin H, which in the drawings is represented as inserted in the head C and in contact with the side of the lugs E² E², thereby holding the piston-rod E against rotation and preventing it from becoming unlocked from the head C. When the piston-rod E is connected with the cross-head D⁹, the pin H is transferred from the head C to the cross-head D⁹ and inserted in a similar hole (indicated by broken lines H' in Fig. 5) and held in contact with the sides of the lugs E³.

The piston-rods E are conical upon each side of the hexagonal section E' for a short distance, as at I I, and the head C and cross-head D⁹ are provided with tapering openings J J, corresponding with the conical sections I I, which are drawn into the openings J J whenever the lugs E² or E³ are locked in their respective chambers F and G.

What I claim as my invention, and desire to secure by Letters Patent, is—

1. In a pumping-engine, the combination with a pump-cylinder and a piston contained therein, of a steam-cylinder, a reciprocating piston in said steam-cylinder, a hollow piston-rod attached to said steam-piston, a piston-rod attached to said pump-piston and inclosed within said hollow piston - rod, and means for connecting said piston-rods, whereby the reciprocating motion of said steam-piston will be imparted to said pump-piston, substantially as described. 105

2. In a pumping-engine, the combination of a steam-cylinder and a pump-cylinder in alinement therewith, reciprocating pistons contained in said steam and pump cylinders, a hollow piston-rod attached to said steam-piston, a head attached to one end of said hollow piston-rod and containing a circular chamber concentric with the hole through said hollow piston-rod and an elongated opening communicating with said circular chamber, a piston-rod attached to said pump-piston and passing through said hollow piston-rod and its attached head, lugs projecting upon opposite sides of said pump piston-rod said lugs being adapted to enter through said elongated opening into said circular chamber and engage the head by the partial rotation of the pump piston-rod, substantially as described. 110

3. In a pumping-engine the combination with a pump-cylinder and a reciprocating piston contained therein, of a steam-cylinder in alinement with said pump-cylinder and provided with concentric stuffing-boxes at opposite ends, a reciprocating piston contained in said steam-cylinder, a hollow piston-rod attached to said steam-piston and ex- 125

tending through said stuffing-boxes at each end of said steam-cylinder, a piston-rod attached to said pump-piston and inclosed in said hollow piston-rod, and means by which 5 said pump piston-rod is disconnected with said hollow piston-rod, substantially as described.

4. In a pumping-engine, the combination of a pump-cylinder and a steam-cylinder in alinement therewith, pistons contained in said cylinders a hollow piston-rod attached to said steam-piston, and extending in opposite directions with a bearing in each end of said steam-cylinder, a head attached to said hollow piston-rod, a piston-rod attached to said pump-piston and passing through said hollow piston-rod and means by which said pump piston-rod is united to said head, substantially as described.

20 5. In a pumping-engine, the combination of a steam-cylinder and pump-cylinder in alinement therewith, pistons contained in said cylinders, a hollow piston-rod attached to said steam-cylinder and extending from said steam-cylinder through opposite ends of said steam-cylinder, a head attached to said hollow piston-rod, valve mechanism by which the flow of steam to said steam-cylinder is controlled, connecting mechanism by which 25 said valve mechanism is operatively connected with said head, a piston-rod attached to said pump-piston and inclosed in said hollow piston-rod, and means by which said pump piston-rod is connected with said head, whereby the reciprocating motion of said steam-cylinder is imparted to said pump-cylinder, substantially as described.

6. In a pumping-engine, the combination with a pump-cylinder, and a piston contained 40 therein, a steam-cylinder and a piston contained therein, of a hollow piston-rod attached to said steam-piston, a piston-rod attached to said pump-piston and passing concentrically

through said hollow piston-rod, means for connecting said pump piston-rod with said steam piston-rods, a rotating driving-shaft, a reciprocating cross-head operatively connected with said driving-shaft, and means for connecting said pump piston-rod with said reciprocating cross-head, whereby said pump-piston is driven by either said steam-piston or said driving-shaft, substantially as described. 45

7. In a pumping-engine, the combination with a steam-cylinder and reciprocating piston contained therein, of a piston-rod attached to said steam-piston, a head carried by said steam piston-rod and provided with a circular concentric chamber and an elongated opening communicating therewith, a rotating driving-shaft, a reciprocating cross-head operatively connected with said shaft and provided with a circular chamber and an elongated opening communicating with said circular chamber, said circular chambers being in alinement, a pump-cylinder, a reciprocating piston in said pump-cylinder, a piston-rod attached to said pump-cylinder and entering the head on said steam piston-rod and also said reciprocating cross-head, a pair of lugs projecting upon opposite sides of said pump piston-rod, and adapted to engage the head on said steam piston-rod, a second pair of lugs on said pump piston-rod arranged in a plane at right angles with said first pair of lugs and adapted to engage said reciprocating cross-head, whereby said pump piston-rod is connected with, or disconnected from said steam piston-rod, head or said reciprocating cross-head by a partial rotation of said pump piston-rod, substantially as described.

Dated the 4th day of February, 1896.
